his Attorneys.

UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

NEEDLE MECHANISM FOR KNITTING-MACHINES.

1,221,807.

Specification of Letters Patent. Patented Apr. 3, 1917.

Application filed March 9, 1916. Serial No. 83,185.

To all whom it may concern:

Be it known that I, ROBERT W. SCOTT, a citizen of the United States, and resident of Boston, in the county of Suffolk and 5 State of Massachusetts, have invented new and useful Improvements in Needle Mechanism for Knitting-Machines, of which the following is a specification.

This invention relates to that class of 10 knitting machine needles employing a sliding member in place of the usual pivoted and swinging latch for the purpose of closing the hook of the needle and casting off the old stitch when the new loop is drawn 15 through the old stitch, one object of my invention being to provide a simple, cheap and effective needle of this class and co-operating devices therefor adapted for machines of fine gage.

20 The ordinary knitting machine latch needle is objectionable for many reasons, among which may be mentioned the length of travel of the needle; the weakening of the same by the latch-receiving slot and the 25 transverse pivot-pin openings; the delicacy of the latch and its pivot pin; the wear upon the latter; the liability of the latch to become broken or bent, thus rendering the needle inoperative; the necessity for the 30 use, in connection with the latch, of an opener therefor, in order to insure the clearing of the hook of the needle for the reception of the fresh yarn; the number of operations necessary to produce the needle, and 35 the consequent cost of the same.

The ordinary latch needle must have a reciprocating movement exceeding twice the length of its latch, and, as, the effective working angle of a needle-actuating cam 40 cannot be greater than 45°, such cams occupy so much space in the cam cylinder, that, in machines of small diameter the use of more than one yarn feed is generally impracticable.

45 The substitution of a sliding hook-closing member for the swinging latch obviates the objections above noted, but, while needles having such sliding members have heretofore been proposed, they have not sup- 50 planted the latch needle because they have not been adapted for use in the fine gage machines now employed for knitting hosiery and underwear.

I am aware of certain attempts in the 55 prior art to provide a practicable needle of

this class, for instance as illustrated by my Letters Patent No. 1,035,752, dated August 13, 1912 [upon which my present invention is an improvement] as well as devices shown in Letters Patent to others, but the said devices were not wholly satisfactory in all situations. In the structure of my said patent, for instance, the sliding hook-closing member lay upon the loop-bearing or front side of the needle, and either required an additional groove in the cam carrier member of the knitting machine, which groove had to be in a place requiring a design of the machine proportions desirable to avoid, or necessitated friction devices co-operating 60 with a part of the needle groove, and means for positively actuating the friction-held parts at times, which latter structures necessitated moving the sliding device with the needle when the needle was abnormally 65 lifted. I was not, therefore, able to wholly avoid enlarging effect upon the withheld loop due to presence of the sliding member in front of the needle shank and in the loop during such times as it was desired to withhold a loop (as the instep loops during heel 70 knitting) well down on the shank of the needle. The other patented devices with which I am familiar, on the other hand do not permit such an abnormal position at all when 75 the knitting is of fine gage, the sliding latch members of said other devices not only being carried by the needle whenever the needle moves beyond the freedom permitted 80 by a short slot in which the head of the 85 hook-closing member can slide, but necessarily being of a thickness preventing their penetration into a knit loop only a little 90 larger than the needle proper.

My present device is particularly designed 95 to enable the needle proper to be made as thin and narrow as proper rigidity will permit, while permitting the hook-closing member to be of such dimensions and so positioned as to permit the needle to stand at an 100 abnormally high position without introducing into a loop held on its shank anything to stretch that loop.

By reason of the improved capacities above mentioned, my new needle is adapted 105 to be operated in a knitting machine organized to place some of the needles out of action in an abnormally elevated position, for instance, to place the instep needles or needles not engaged in heel-and-toe knitting 110

out of action in a high position during reciprocatory knitting for heel or toe on the other needles.

In the accompanying drawings,

5 Figure 1 is a section through a needle carrier on the line 1—1 of Fig. 2, illustrating my new needle and devices adapted to coöperate therewith;

10 Fig. 2 is a section on the line 2—2 of Fig. 1 on an enlarged scale;

Fig. 3 is a longitudinal section of the needle shown in Fig. 1 on an enlarged scale showing the hook-closing device open;

15 Fig. 4 is a similar section showing the hook-closing device closed;

Fig. 5 is a view similar to Fig. 3 illustrating a modified form;

20 Figs. 6 and 7 are respectively views partly in section illustrating a further modification in a closed and in an open position; and

Fig. 8 is a diagram section illustrating the needle, the hook-closing tongue and a knit loop.

25 The needle comprises a shank 1 and operating butt 2 of any known or usual construction, said shank ending in hook 3, which may stand in any desired relation to the front line of the shank, for instance as shown in Fig. 1 or as shown in Fig. 5.

30 The shank is penetrated at a point beneath the hook by a slot which may be a saw kerf having sloping ends, as shown in Figs. 1, 3 and 5, of which the upper end 4 constitutes a cam face substantially directed at the point 35 of the hook 3.

In the form illustrated in Figs. 1 and 3, the back of the needle is grooved at 5, so as to permit the bottom of the groove to be in line with the slope 4.

40 Coöoperating with the needle proper a sliding hoop-closing member 6 of spring metal is provided with a spring tongue 7 which, in the form illustrated in Figs. 1 to 4, is comprised of a normally straight, reduced portion of the member 6. The needle carrier 8 is provided with the usual needle slots 9, and with narrower slots 10, preferably central with respect to the needle slots as shown in Fig. 2, in which slots 10 the members 6 are 50 arranged to slide with friction, for instance having an impressed bend when free.

45 As illustrated in Fig. 1, the members 6 may have operating butts 12, each adapted to take into a recess 13 formed in the needle shank 1. The butt 12 is so situated with respect to the recess 13 as to cause the normal stitching movement of the needle to advance the tongue 7 substantially to the position with respect to the needle carrier illustrated 60 in Fig. 1, so that when the needle is in a normal or middle position, the point of the tongue 7 occupies the position relative to the needle illustrated in Figs. 1 and 3. Further downward movement of the needle will now 65 cause the spring tongue 7 to be displaced by

the cam slope 4, and to penetrate the slot in the needle shank to the position indicated in Fig. 4, at which the needle hook is closed. Further downward movement of the needle will cause the upper end of the recess 13 to 70 encounter the butt 12 of the member 6, the parts moving together until the old loop has been cast off, and the needle is completely immersed in its groove 9.

The tongue 7 in all positions of the needle 75 hugs the back thereof closely, so that when the needle is lifted to the abnormal position illustrated in dotted lines in Fig. 1, the thin spring tongue 8 may stand in a relation to the loop *a* then on the shank of the needle 80 illustrated in Fig. 7, the spring tongue occupying a triangular opening normally left at the back of the needle even by a loop knit so tightly as it is possible to move freely on the shank of the needle.

85 In some cases, as illustrated in Fig. 5, the needle need not be reduced at the back so as to make the cam wall of the slot in the needle shank stand beyond the bottom of groove 5, the tongue 7 in this case being provided with 90 an impressed bend 14 so as to find and enter the slot in the shank.

95 As illustrated in Figs. 6 and 7, such a hook-closing member may be so made as to perform the desired functions without causing it to be bent forward at each stroke of the needle, the hook-closing element being rocked or tilted forward on relative movement of the parts. As shown, a thin spring-metal hook-closing member 15 may be recessed at 16 to leave an operating butt 17 adapted to work in the recess 13 of the shank of a needle 20, a thin tongue 18 of the member 15 lying substantially in front of the shank of the member 15 and terminating in 100 a hook engaging bend 19. The needle is provided with a slot 5 deep enough substantially to inclose the tongue 18 in the open position shown in Fig. 7. The needle shank is slotted to provide a slope 4 as explained in 105 connection with Figs. 1 to 5.

110 The parts when placed in such a carrier as shown in Figs. 1 and 2 assume the relative positions shown in Figs. 6 and 7 at opposite ends of a stroke of the needle 20 sufficient to cause butt 17 to traverse recess 13, and further upward movement of a needle 20 which has been adjusted as in Fig. 7 may take place, within the distance measured by the thin tongue 18, without introducing into a 115 loop held on the shank of the needle anything thicker than the needle shank. The needles 1 and 20 are therefore all well adapted to be placed out of action while holding their loops with their butts at a relatively high level with respect to the needle-carrier 120 and the knitting cams.

125 It will be understood that while the relative dimensions of the thin tongues 7 or 18, and the freedom for relative motion per-

mitted between the recesses 13 and the butts 12 or 17 are as illustrated, practicable instances of proper proportions of the parts, such proportions may be varied to suit variable conditions of use, such as different relative distances between the active and inactive paths for the butts 2, and that the species shown are illustrative only of the genus of my invention.

10 What I claim is:

1. The combination with a knitting machine needle having a slotted shank grooved at the back and a hook opening on the face thereof, of a sliding hook-closing member 15 adapted to slide on the back of said needle, said member having a long narrow tongue normally housed within said groove and adapted to be moved forward and outward by a cam surface on said needle through said 20 slot and into closing relation to said hook upon relative movement of said needle and said member in one direction.

2. A knitting machine needle having a shank ending in a hook opening on one face 25 of the shank, in combination with a member having a relatively long thin hook-closing tongue movable in a groove on the other face of the needle shank, said needle having therein an opening having a cam end adapted 30 to move said tongue into position to close said hook on relative movement of said member toward the hook end of said needle, whereby the needle is adapted to have its hook end moved to a much greater distance 35 than necessary for knitting through a yarn loop on its shank without introducing into said loop parts tending to enlarge the same.

3. A knitting machine needle having a slotted shank and a hook opening on one 40 face thereof; and a sliding hook-closing member adapted to slide on the other or back face of said needle, said member having a spring tongue adapted to be bent by one margin of said slot into closing relation 45 to said hook upon relative movement of

said needle and said member in one direction.

4. In a knitting machine, the combination of a hooked needle having a shank and an opening therein with a carrier having a 50 groove for said needle, a groove at the bottom of the needle groove for frictionally holding a hook-closing member, and a hook-closing member in said latter groove having a long thin tongue adapted to pass through 55 the opening in the needle shank into closing relation with the needle hook, and means permitting movement of said needle relatively with respect to said member respectively to effect such passage and closure, and 60 to hold said tongue parallel with the needle shank and withdrawn from the hook.

5. In a knitting machine, the combination of a needle having a hook and a shank, having an opening therein near said hook, with 65 a carrier having a groove for said needle, a groove at the bottom of the needle groove for frictionally holding a hook-closing member, and a hook-closing member in said latter groove having a tongue adapted to enter 70 and pass through said opening in the needle shank into closing relation with said needle hook, and means independent of said opening for positively moving said hook-closing member with said needle at the extremes of 75 the movement of said needle.

6. A hook-closing member for coöperation with a knitting needle having a slot therein and a hook thereon comprising a shank adapted to be frictionally held in a 80 grooved carrier, and a normally straight spring tongue thereon adapted to lie closely against the back of said needle, whereby to enter said slot and close said hook during relative movement between said member and 85 said needle.

Signed by me at Boston, Massachusetts, this 7th day of March, 1916.

ROBERT W. SCOTT.
